UNITED STATES PATENT OFFICE.

ANDREW B. HENDRYX, OF NEW HAVEN, CONNECTICUT.

DESIGN FOR A BIRD-CAGE HOOK.

SPECIFICATION forming part of Design No. 28,158, dated January 11, 1898.

Application filed December 6, 1897. Serial No. 660,981. Term of patent 14 years.

To all whom it may concern:

Be it known that I, ANDREW B. HENDRYX, of New Haven, in the county of New Haven and State of Connecticut, have invented a new 5 Design for Bird-Cage Hooks; and I do hereby declare the following, when taken in connection with the accompanying drawings and the letters of reference marked thereon, to be a full, clear, and exact description of the same, 10 and which said drawings constitute part of this specification, and represent, in—

Figure 1, a side view; Fig. 2, a section on line *a b* of Fig. 1.

This invention relates to a design for bird- 15 cage hooks; and the design consists in the configuration and ornamentation of the hook, as herein shown and described.

The design consists of a bar A, terminating in a downwardly and upwardly turned hook B. On each side of the bar is a rib C, which 20 rib extends from the base D throughout the entire length thereof and merging into the bar at the point E of the hook.

I claim—

The design for a bird-cage hook as herein 25 shown and described.

In testimony whereof I have signed this specification in the presence of two subscribing witnesses.

ANDREW B. HENDRYX.
